(57) **CLAIM**

I claim the ornamental design for a radar sensor, as shown and described.

DESCRIPTION

1. Radar sensor

FIG. 1.1 is a line drawing evidencing a perspective view of the design;

FIG. 1.2 is a line drawing evidencing a front view of the design;

FIG. 1.3 is a line drawing evidencing a back view of the design;

FIG. 1.4 is a line drawing evidencing a right side view of the design;

FIG. 1.5 is a line drawing evidencing a left side view of the design;

FIG. 1.6 is a line drawing evidencing a top view of the design; and

FIG. 1.7 is a line drawing evidencing a bottom view of the design.
